UNITED STATES PATENT OFFICE

154,885

DESIGN FOR A COMBINATION ASH TRAY, GLASS HOLDER, OR SIMILAR ARTICLE

Albert J. Sesona, Jr., Quincy, Mass.

Application May 5, 1948, Serial No. 146,176

Term of patent 3½ years

(Cl. D85—2)

To all whom it may concern:

Be it known that I, Albert J. Sesona, Jr., a citizen of the United States and resident of Quincy, county of Norfolk, and State of Massachusetts, have invented a new, original, and ornamental Design for a Combination Ash Tray, Glass Holder, or Similar Article, of which the following is a specification, reference being made to the accompanying drawing, forming part thereof.

In the drawings:

Fig. 1 is a perspective view of a combination

ash tray, glass holder, or similar article, showing my new design; and

Fig. 2 is a perspective view thereof, in unassembled form.

I claim:

The ornamental design for a combination ash tray, glass holder, or similar article, substantially as shown.

ALBERT J. SESONA, JR.
